CLAIM

The ornamental design for a display screen or portion thereof with animated graphical user interface for displaying market information as shown and described.

DESCRIPTION

1. Display screen or portion thereof with animated graphical user interface for displaying

1.1 : Front

1.2 : Front

1.3 : Front

1.9 : Front

1.10 : Front

Broken lines in the reproductions illustrate the display screen or portion thereof. The appearance of the transitional image sequentially transitions between the images shown in Figs. 1.1-1.2-1.3-1.9-1.10. The process or period in which one image transitions to another image forms no part of the claimed design.

Texts including Chinese characters, numbers, and elements comprised of an X or row of Xs do not form part of the claimed design.
